UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

FIRE-PREVENTING DEVICE FOR MOTION-PICTURE MACHINES.

Application filed May 17, 1913, Serial No. 768,210. Renewed December 17, 1919. Serial No. 345,583.

To all whom it may concern:

Be it known that I, NICHOLAS POWER, a citizen of the United States, and a resident of Brooklyn, in the county of Kings and State of New York, have invented new and useful Improvements in Fire-Preventing Devices for Motion-Picture Machines, of which the following is a specification.

This invention relates to safety mechanisms for moving picture projecting machines and particularly to mechanisms for preventing the ignition of the film from the heat of the projecting arc or lamp. In motion picture projecting machines as now generally constructed the essential elements comprise an electric arc or other powerful and intense light with lenses for condensing the same on a picture and projecting the picture on the screen, a frame having an aperture corresponding in size and shape to the individual pictures on the strip, and a feed mechanism for intermittently feeding the successive pictures into registration with the aperture upon which the rays of light are condensed. The picture strips are composed of celluloid and are highly inflammable, so much so that if the picture remains stationary in the path of the rays of light for an appreciable time it will be ignited by the intense heat of the light and perhaps cause a serious catastrophe, for even though the utmost care be employed in the matter of safeguards such as fire proof booths for the operators, the odor of the burning film will often cause a panic in crowded theatres when the loss from the fire itself is most trivial.

To protect the film from the heat of the projecting lamp the projecting machines are provided with screens which at all times cover the face of the film toward the light save the particular picture opposite the projection aperture, and when the machine is not in operation this portion of the strip is covered by a door or "fire shield" which automatically closes the moment the rotation of the driving shaft ceases.

It sometimes happens however that the film will break below the projection aperture leaving a portion of the film stationary in the projection aperture even though the rotation of the driving sprocket be continued, or it may happen that the film feeding devices slip or otherwise fail to feed the film so that

it will remain stationary in line with the projection aperture long enough to become ignited, and it is the object of my present invention to provide means operating automatically upon the breaking of the film or any failure of the feed mechanism to cut off the light from the projection aperture and thereby prevent the film becoming ignited whether or not the driving shaft be continued in operation.

In the accompanying drawings I have illustrated a preferred embodiment of my invention wherein I accomplish the above mentioned results by means of a novel device operating to close the automatic fire shield and also stop the feeding of the film from the magazine upon a departure of the film from its normal path of movement, such as would be caused by a breakage of the film or a portion of the feeding mechanism. It will of course be understood that other mechanisms than the one disclosed may be employed for the purpose, and also that other forms of safety devices may be operated in place of or in addition to the fire shield, and that my invention is not therefore limited to the construction shown and described, but instead covers all such modifications thereof as fall within the scope of the appended claims.

In the accompanying drawings Figure 1 is a side elevation partly in section of a portion of a moving picture machine equipped with my improved safety mechanisms;

Fig. 2 is a plan view of the mechanisms shown in Figure 1 and

Figs. 3 to 5 are sectional details which will be later described. Fig. 6 is a sectional view of a modification.

Referring now to the drawings in which like parts are indicated by like characters throughout the several views, 1 indicates the frame of a projecting machine in which the film feeding mechanism is supported. Rotatably mounted in the frame 1 is a driving shaft 2 which may be operated by a crank handle or power motor as desired. On top of the frame 1 a bracket 3 is provided in which is rotatably mounted a shaft 4 for the upper feed sprocket 5. The sprocket 5 is continuously rotated as will be hereinafter described to feed the film 6 from an upper magazine not shown. From the sprocket 5 the film passes downward past the projection aperture 7 in the rear wall of the frame

1 into engagement with a sprocket 8 which is intermittently rotated from the main shaft 2 by suitable intermediate gearing 9 to successively feed the pictures on the strip into 5 registration with the aperture. The intermittent sprocket 8 remains stationary during the interval that the shutter of the machine is open while the picture is being projected, and then while the shutter is closed is given 10 a partial rotation to feed the picture strip a sufficient distance to bring the next picture into registration with the aperture. After leaving the intermittent sprocket 8 the film passes downward over a lower continuously 15 operated sprocket 9^a and thence into a receiving magazine where it is wound on a suitable reel.

It will of course be understood that the interval that any one picture is stationary 20 in the normal operation of the machine is not sufficient for the film to become heated to the point of ignition.

For holding the film in engagement with the upper sprocket 5 I preferably provide 25 an idler 10 movably mounted in any suitable manner to permit easy threading of the machine. The idler 10 directs the film in an upward direction so that it turns and forms a loop as shown in full lines at 11 in Figure 3 before it reaches the guide-springs adjacent the projection aperture. The machine is preferably threaded up with a loop of 30 about the size shown which will be maintained about the same size throughout the 35 operation of the machine varying merely the amount fed at each single operation of the intermittent sprocket. The guide-springs 12 are mounted on the inner face of the rear door 13 of the machine which is closed 40 against the film so that the springs hold the film in proper alignment with the projection aperture. The door 13 is provided with apertures 15 of the same size and shape as the aperture 7, and covering the apertures 45 15 is a fire shield 16 which is hinged on a rod 17 extending across the rear face of the door above the aperture.

For operating the door 16 an arm 18 is attached to the rod 17 at one end which projects slightly beyond the side wall of the frame or head 1. When the door is closed the arm 18 extends rearwardly and upwardly from the rod as shown in full lines in Figure 1 and lies beneath a pin 19 in the 50 side of a link 20 which is pivotally mounted at its lower end to a lever 20^a fulcrumed on a pin 20^b in the side wall of the casing. The lever 20^a is connected at its other end by a suitable pivot to the casing 21 of a centrifugal clutch 22 carried by a shaft 23 driven at high speed from the shaft 4 by means of a gear 30 and suitable connections. When the machine is being operated with sufficient speed for the centrifugal clutch members to 55 engage their casing 21, the lever 20^a will

turn on its pivot thereby depressing the pin 19 and the arm 18 and opening the fire shield. As the fire shield is very easy to operate the centrifugal clutch has but a light grip so that after the fire shield is raised the 70 clutch will slip on the continued rotation of its shaft and hold the shield raised as long as the speed of operation is sufficient to keep the clutch members thrown out against the periphery of the casing. 75

The mechanism as above described constitutes the film feeding mechanism of one well known form of moving picture machine, the upper sprocket 5 being in such machine driven by a gear wheel fast on the shaft 4 80 and driven from a gear on the driving shaft 2. In the construction forming my present invention the gear wheel 25 for the upper sprocket is not fastened on the shaft 4 but is mounted for independent rotation and is 85 provided on its inner face with a clutch member 26 adapted to be engaged by a similar clutch member 27 having a clutch face 28. The hub of the clutch member 27 is elongated to form a sleeve 29 in which is 90 formed a spiral slot. Mounted on the sleeve 29 between the clutch face 28 and a collar 28' is a ratchet wheel 31. The hub of the ratchet is provided with a keyway 32 which overlies the spiral slot in the clutch member 95 27 and receives the end of a pin 32^a passing through the slot and fast in the shaft 4. A spring is arranged between the ratchet and clutch member to normally hold the clutch members 26 and 27 in engagement. 100

The bracket 3 is provided with an arm adjacent the ratchet 31 and pivotally mounted on this arm is a pawl 33 for co-operation with the ratchet. It will be obvious that when the machine is in operation with the clutch members in engagement, the shaft 4 and the ratchet wheel 31 will be rotated with the clutch member 27 through the pin and slot connection, but if the pawl 33 be dropped into engagement with the ratchet the ratchet will be stopped but the clutch member 26 will continue in motion by reason of its engagement with the positively driven gear wheel 25, and the spiral slot turning against the stationary pin 32^a will move the clutch member 27 away from the gear 25 and thereby release the clutch and permit the upper sprocket to stop, while the rest of the mechanism may continue in motion. 110 115

Any suitable means may be provided to operate the pawl 33 upon the breakage of the film or other failure of the film feeding mechanism. In this application I have disclosed a novel and preferred mechanism for this purpose which mechanism, in addition to operating the pawl 33, also positively closes the fire shield 16 whenever the upper feed sprocket is unclutched as described. This mechanism comprises a chute or casing 35 enclosing the upper loop 11 of the film 120 125 130

between the sprocket 5 and the guide roller 10. For convenience in threading the machine the chute 35 is formed of two pieces 35^a and 35^b. The part 35^a consists of a piece of sheet metal of angular cross section forming one side and one end of the chute rigidly supported immediately above the sprocket 5 by means of a bracket 36. The part 35^b is also composed of a piece of sheet metal of angular cross section and is rigidly attached to the upper edge of the door 13 so that when the door is closed it will lie adjacent the part 35^a and form with it a rectangular casing completely enclosing the film. A cover 37 consisting of a comparatively heavy piece of metal is hinged along one edge to the upper edge of the long side of the piece 35^a and normally rests of its own weight on the upper edges 10 of the chute 35. At the end adjacent the ratchet wheel 31 the cover is provided with a rearwardly extending arm 38 to which is pivotally connected a rod 39 whose lower end passes through an eye 40 formed on the 20 pawl 33. Immediately beneath the eye 40 the rod 39 is provided with a collar 41 which when the cover 37 is closed and the arm 38 elevated will hold the pawl out of engagement with the ratchet but which 25 30 when the cover is raised and the arm 38 depressed will allow the pawl to drop of its own weight into engagement with the ratchet.

The cover 37 is provided at its opposite 35 end with an arm 42 to which is connected a link 50 whose other end is pivotally connected to the horizontal arm of a bell crank 51 pivoted on the frame 1 above the end of the lever 20^a. The vertical arm of the bell 40 crank lies behind the link 20 and is provided with a pin 52 projecting through a slot in the link and holding the link in such 45 position that when the fire shield 16 is in its open position, as shown by dotted lines in Figure 1, and the cover 37 is closed, the pin 19 will engage the arm 18 but if the cover be raised, as will be later described, the arm 51 will turn the arm 20 to cause the pin 19 to release the arm 18 allowing the 50 fire shield to close.

The operation of the mechanism will now be described. As explained above, the loop 11 in the normal operation of the machine is substantially constant in size as the intermittent sprocket draws the film out of the chute as rapidly as it is fed thereto by the continuous sprocket 5. If however for any reason the intermittent sprocket fails to feed the film, as for instance when the 55 sprocket holes in the margin of the film are torn or mutilated, the film will be no longer drawn from the chute for the springs 12 act as a brake on the film above the intermittent sprocket, thereby necessitating a 60 positive engagement of the film to effect its

movement. The film will however continue to be fed into the chute for the sprocket 5 is rotated continuously and as it merely feeds the film from the upper reel, the resistance is so slight that a mere frictional engagement is sufficient to effect the feeding of the film even though all the sprocket holes be entirely worn out. The accumulation of the film in the chute causes the film to press up against the cover 37. 75 lifting the same and thereby depressing the arms 38 and 42 allowing the pawl 33 to engage the ratchet wheel 31 and unclutch the sprocket 5 so that no more film will be fed from the reel, and also positively closing 80 the fire shield 16 thereby cutting off the rays of light from the projecting lamp before the film becomes heated to the point of ignition. The closure of the fire shield also cuts off the picture from the screen and 85 therefore notifies the operator who can immediately stop the machine and reset the machine for normal operation. As the ratchet is mounted between the clutch rim 28 and the collar 28' it will move longitudinally with the clutch member 27 and when the clutch is disengaged the pawl will drop behind the ratchet and hold the clutch 90 out of engagement.

It sometimes happens that a badly mutilated film will be fed past the sprocket 5 but will break when in the chute in the manner indicated by dotted lines in Figure 3, so that a free end of the film will be forced against the cover 37. In such cases there would be 100 a tendency for the end of the film to escape from the chute without raising the cover sufficiently to operate the clutch or fire shield. To prevent this I form the cover with a curved lip which projects slightly 105 within the chute as shown, and acts to deflect the end of the film over against the rear wall of the chute where it will be stopped by the guide roller 10 and thereby 110 form a loop in the film to raise the cover and operate the safety mechanism in the manner above described.

In Fig. 6 I have shown a slightly modified form of clutch mechanism for the upper sprocket. As here shown the shaft 4 has attached to one end a disk 60 having a clutch pin 61. Adjacent the disk 60 is the driving gear 62 loose on the shaft and having a pin 63 slidably mounted in a hole in the gear parallel to the shaft. The end of the pin 115 is provided with a shoe rotatably engaging a groove in the hub of a cam 64 keyed to the shaft. The rim of the cam is provided with inclined cam faces adapted to be engaged by a pin in the end of the pawl 33^a and shift the clutch pin 63 out of engagement with the pin 61 when the operation of the lid 37 allows the pawl to drop. The pawl 33^a of the modified form is of the same construction as the pawl 33 of the first described 120 125 130

construction except that it is provided with a downwardly projecting pin to engage the cam faces of the clutch member instead of with the usual point to lock with the ratchet teeth. The pawl 33^a will be connected to the cover 37 of the film guide in the same manner as the pawl 33 of the first described construction.

The operation of this form of mechanism 10 will be obvious from inspection; when the cover 37 is raised by the film the pin in the end of the pawl 33^a will come into engagement with the inclined cam faces of the clutch member 64 so that the rotation of the 15 sprocket shaft will cause the clutch member to laterally shift, withdrawing the pin 63 from engagement with the pin 61. The shoulder at the end of the cam face as shown in dotted lines in Fig. 6 will engage 20 the pin of the pawl 33^a and thereby hold the clutch against further rotation, thus stopping the sprocket while permitting the free rotation of the driving gear 62. When the 25 loop of film is reduced to normal proportions either by the continued operation of the machine in case the fault should be self-adjusting, or by the operator, the weight of the cap 37 will lift the pawl 33^a out of engagement with the member 64 so that the spring 30 will re-engage the clutch and cause the sprocket to be again driven from the gear 62.

It will of course be understood that the fire shield operating device may be used 35 without the clutch actuating mechanism for the upper sprocket, but I prefer to use both devices for the reason that the film is fed quite rapidly and should the operator's attention be attracted away from the picture on the screen he might operate the machine 40 long enough after the fire shield had cut off the picture to feed a large quantity of the film out of the chute where it will be in danger of getting caught in the mechanism of the machine or otherwise damaged.

Having thus described my invention, what 45 I claim and desire to secure by Letters Patent is:—

1. In a motion picture machine the combination of a plurality of successive film 50 feeding devices and means operated by an accumulation of film between said feed devices for stopping the first of said devices without stopping the succeeding devices.

2. In a motion picture projecting machine 55 the combination of relative successive film feeding devices for feeding the film past the projection aperture, independent driving mechanism therefor, a shutter for screening said aperture from the light, connections between said shutter and said driving mechanism for operating the shutter to uncover the aperture when the machine is operating, auxiliary means for closing said shutter, said means comprising a member 60 positioned to be engaged by the film on a

departure from its normal path of movement, connections whereby movement of said member as effected by said film closes the screen, and means operated by said member for stopping the first of said film feeding 70 devices without stopping the machine.

3. In a motion picture projecting machine, the combination of a plurality of successive film feeding devices for feeding the film with a loop of slack between said devices, a guide 75 for the loop of film for causing the enlargement of said loop to exert a thrust in a predetermined direction, means for controlling the operation of said feeding devices to prevent excessive enlargement of the loop without stopping the machine, a movable member positioned to be operated by the thrust of the film upon the enlargement of the loop, and motion transmitting connections between said member and an element of said means 85 whereby movement of said member controls said means.

4. In a motion picture machine the combination of a plurality of successive film feeding devices, a guide for causing the enlargement of a loop of film between said devices to project in a predetermined direction, means for rendering one of said feeding devices inoperative without stopping the machine, and means for operating said first-mentioned means comprising a member movably mounted in the path of enlargement of said loop and a member normally out of engagement with said loop and adapted to be actuated by the thrust of the film upon an enlargement of the loop, and motion transmitting connections between said member and said first mentioned means. 100

5. In a motion picture machine having a source of light, the combination of a plurality of successive film feeding devices for feeding the film across the path of light, a guide for causing an enlargement of a loop of film between said devices to project in a predetermined direction a member normally 105 out of engagement with said loop and adapted to be actuated by the thrust of the film upon an enlargement of said loop and means operated by the movement of said member for rendering the first of said feeding devices inoperative and for cutting off the light from the film without stopping the machine. 110

6. In a motion picture machine, the combination with an intermittently and a continuously rotated sprocket, a film guide located between said sprockets and adapted to be moved by an increase in the size of a loop in the film and means actuated by the movement of said guide for controlling the 115 operation of said continuously rotating sprocket without otherwise affecting the operation of the machines. 120

7. In a motion picture machine, the combination with intermittent and continuous 125

sprockets of means interposed between said sprockets and controlled by an increase in the size of the loop formed in the film between said sprockets for controlling the 5 operation of said continuously rotating sprocket without affecting the operation of the other parts of the machine.

Signed at New York, in the county of New York and State of New York, this 14th day of May, 1913.

NICHOLAS POWER.
